(57) **CLAIM**

The ornamental design for spherical guide tips scissors, as shown and described.

DESCRIPTION

FIG. 1 is a perspective view of my new design for spherical guide tip scissors shown in a closed position;

FIG. 2 is a perspective view of my new design for spherical guide tip scissors shown in a open position;

FIG. 3 is a right side elevation view of my new design for spherical guide tip scissors shown in a closed position;

FIG. 4 is a left side elevation view of my new design for spherical guide tip scissors shown in a closed position;

FIG. 5 is a front top elevation view of my new design for spherical guide tip scissors shown in a closed position;

FIG. 6 is a front bottom elevation view of my new design for spherical guide tip scissors shown in a closed position;

FIG. 7 is a top plan view of my new design for spherical guide tip scissors shown in a closed position;

FIG. 8 is a bottom plan view of my new design for spherical guide tip scissors shown in a closed position;

FIG. 9 is an enlarged partial perspective view of my new design for spherical guide tip scissors shown in a closed position;

FIG. 10 is an enlarged partial perspective view of my new design for spherical guide tip scissors shown in an open position;

FIG. 11 is an enlarged partial right side view of my new design for spherical guide tip scissors shown in an closed position;

FIG. 12 is an enlarged partial left side view of my new design for spherical guide tip scissors shown in an closed position;

FIG. 13 is an enlarged partial top plan view of my new design for spherical guide tip scissors shown in an closed position;

FIG. 14 is an enlarged partial bottom plan view of my new design for spherical guide tip scissors shown in an closed position;

FIG. 15 is another top plan view of my new design for spherical guide tip scissors shown in a closed position, and shown with alternative unclaimed subject matter as being applied to a thinning scissors;

FIG. 16 is another top plan view of my new design for spherical guide tip scissors shown in an open position, and shown with alternative unclaimed subject matter as being applied to a removable blade scissors; and,

FIG. 17 is another perspective view of my new design for spherical guide tip scissors shown in a closed position, and shown with alternative unclaimed subject matter as being applied to a curved blade scissors.

(Continued)

The broken lines illustrate portions of the spherical guide tip
scissors that form no part of the claimed design.
